The ornamental design for an injector shield, as shown and described.

DESCRIPTION

FIG. 1 is a perspective view of an injector shield, showing our new design;

FIG. 2 is a side view thereof;

FIG. 3 is a front view thereof;

FIG. 4 is a rear view thereof;

FIG. 5 is side view thereof;

FIG. 6 is a bottom view thereof; and,

FIG. 7 is a perspective view thereof.

The broken lines in FIGS. 1-7 are for the purpose of illustrating environmental structure and form no part of the claimed design. The line of alternating dots and dashes in FIG. 6 is a boundary line that defines the bounds of the claimed design and forms no part thereof. Oblique line shading in FIGS. 1-5 and 7 indicates a transparent or translucent appearance.
